UNITED STATES PATENT OFFICE.

THOMAS J. KEHOE, OF FORT WAYNE, INDIANA.

OIL-FEEDING DEVICE.

No. 811,840.

Specification of Letters Patent.

Patented Feb. 6, 1906.

Application filed June 9, 1905. Serial No. 264,387.

To all whom it may concern.

Be it known that I, THOMAS J. KEHOE, a citizen of the United States of America, and a resident of Fort Wayne, in the county of Allen and State of Indiana, have invented 5 certain new and useful Improvements in Oil-Feeding Devices, of which the following is a specification.

This invention relates to improvements in 10 oil-feeding devices; and the object thereof is to afford mechanism of simple construction by means of which lubricating-oil will become discharged by force from a fountain through a series of independent leads.

15 The above object is accomplished by the construction illustrated in the accompanying drawings, in which—

Figure 1 is a front view of the device shown partially in longitudinal section, and Fig. 2 is 20 a central transverse sectional view of the same.

Similar numerals of reference indicate corresponding parts in both views, and, referring now to the same, 1 is an elongated horizontal fountain having a series of independent leads 2, depending from the lower part thereof, each having a central bore 3, which extends into and communicates with the fountain.

30 A revoluble shaft 4 ranges longitudinally through the center of the fountain and is supported in the heads 5 and 6 thereof, and an eccentric 7 is rigidly fixed upon said shaft approximately in the middle of the fountain, respecting its length. A worm-wheel 8 is rigidly fixed upon the shaft 4 at a point thereon within the head 6; and a driving-worm 9 engages the worm-wheel and actuates the latter, the worm being mounted upon 35 the driving-shaft 10, which extends into the head 6. A stuffing-box 11 is arranged in connection with the head 6 for the driving-shaft 10. It will thus appear that when the driving-shaft 10 is rotated the eccentric 7 will accordingly be actuated.

40 A yoke 12 is arranged in engagement with the eccentric 7 within the fountain and has a hollow vertical stem 13 extending from its upper part, the stem extending into a guide-opening 14, which leads from the top of the fountain. The lower part of the yoke has a horizontal bar 15 in connection therewith, and attached to the bar 15 is a series of independent hollow plungers 16, which extend, respectively, into the bores 3 of the leads 2 and are vertically movable therein. The said

plungers are closed at their tops and open at their lower ends, and each has a side port 17, which communicates with the fountain when the plunger is in its uppermost position. 60

Each of the leads 2 has a seat 18, which faces downward and is annular, and a valve 19 is arranged one within each of the leads, each valve having a shoulder 20, which normally rests upon the corresponding seat 18. 65 The valves 19 are hollow and are open at their tops and closed at their lower ends and have side ports 21, which communicate with the lower part of the leads beneath the seat 18 when the respective valves become depressed 70 as hereinafter described. A spring 22 is arranged one within the lower part of each of said leads and acts upwardly against the corresponding valve 19 to hold the latter in normal closed relation with the seat 18, and an outlet-opening 23 is made at the lower end of each of said leads for the discharge of oil therefrom.

Each lead has a glass cylinder 24 in its lower portion beneath the valve, and sight- 80 openings 25 are made in the leads at points adjacent their glass cylinders which render the lower part of their interiors visible.

The various bearings of any machine requiring lubrication may be connected, respectively, with the lower ends of the leads by means of suitable pipes, (not shown,) so as to receive the discharge of oil through the corresponding openings 23.

The fountain is charged with oil from any 90 suitable source of supply through the projection 26 and stem 13, and when filled and the driving-shaft is set in continuous rotary motion the plunger 16 will be reciprocated vertically in unity, and when in their uppermost 95 positions the oil in the fountain will gravitate through the ports 17 into the respective leads, but will become retarded from further downward passage because of the valves 19. When the plungers are moved downward, 100 their ports 17 will become closed at the beginning of their downward stroke, and the oil contained in the leads between the plungers and valves will be forced by the downward movement of said plungers, which will have 105 the effect of pressing the valves downward, so as to compress the springs 22. When the valves are so pressed downward, the oil above said valves will escape through the ports 21, as said ports pass the seats 18, respectively, and from thence the oil will gravitate to and from the discharge-openings 23. It will ap-

pear that the oil between the plungers and valves will be detained above the valves until the valves become moved downward, and the respective ports afford relief for the oil by 5 passing the corresponding seats, and therefore if any of the ports 21 are located at various distances above the respective shoulders 20, as indicated in dotted outline at 27, the discharge of oil through the corresponding 10 leads will vary in quantity accordingly.

Having described my invention, what I claim as new, and desire to secure by Letters Patent, is—

1. In mechanism of the class described, a 15 fountain having a series of independent leads communicating with its lower part; a series of plungers working in the leads respectively and each plunger having means in connection therewith for admission of oil from the fountain into the corresponding lead when the plunger is in uppermost position; outlet-valves arranged one in each of the leads, and located therein beneath the corresponding plungers; and mechanism in connection with 20 the plungers to actuate the same.

2. In mechanism of the class described, a fountain having a series of independent leads communicating with its lower part; a series of plungers working in the leads respectively, 30 and each plunger having means in connection therewith for admission of oil from the fountain into the corresponding lead when the plunger is in uppermost position; outlet-valves arranged one in each of the leads beneath the corresponding plungers, each valve being hollow, open at its top, and closed at its lower end, and having an annular shoulder which rests against a seat in the corresponding lead, and having also a port which affords 40 communication for the downward passage of

oil within the lead when the valve is moved below its normal position; compression-springs acting one against each of the valves to hold the latter in normal position; and mechanism in connection with the plungers 45 to actuate the same.

3. In mechanism of the class described, a fountain having one or more leads communicating with its lower port; plungers working in the leads respectively, each being hollow, 50 closed at its top, and open at its lower end, and having a side port which affords communication for the passage of oil from the fountain into the corresponding lead when the plunger is in uppermost position; an outlet-valve in each of the leads at points therein below the corresponding plunger; and mechanism in connection with the plungers to actuate the same.

4. In mechanism of the class described, a 60 fountain having independent leads communicating with its lower part each lead having an outlet-valve; plungers working one in each lead, each plunger having means in connection therewith for admission of oil from the fountain into the corresponding lead when the plunger is in uppermost position; a yoke 65 within the fountain, having connection with each plunger, and having also means in connection therewith to guide its movement; 70 and a shaft extending within the fountain and having an eccentric mounted thereon, the latter engaging the yoke to actuate the same.

In testimony whereof I affix my signature 75 in presence of two witnesses.

THOMAS J. KEHOE.
